UNITED STATES PATENT OFFICE.

ABRAHAM BEVER, OF STELLA, NEBRASKA.

VEHICLE-SHAFT.

SPECIFICATION forming part of Letters Patent No. 774,032, dated November 1, 1904.

Application filed February 8, 1904. Serial No. 191,815. (No model.)

To all whom it may concern:

Be it known that I, ABRAHAM BEVER, a citizen of the United States, residing at Stella, in the county of Richardson, State of Nebraska, have invented certain new and useful Improvements in Vehicle-Shafts; and I do hereby declare the following to be a full, clear, and exact description of the invention, such as will enable others skilled in the art to which it appertains to make and use the same.

This invention relates to vehicle-shafts; and it has for its object to provide a construction wherein the cross-bar will be so formed and connected to the shaft sides that it will permit of movement of the sides with respect to each other without placing a breaking strain on the cross-bar.

Other objects and advantages of the invention will be understood from the following description.

In the drawings forming a portion of this specification and in which like numerals of reference indicate similar parts in the several views, Figure 1 is a perspective view showing vehicle-shafts embodying the present invention. Fig. 2 is a section taken longitudinally through the cross-bar and transversely through the shaft sides.

Referring now to the drawings, there is shown a pair of shafts comprising sides 5 and 6. Secured against the inner faces of the shaft sides are brackets 7 and 8, which are held in place by means of bolts and to which brackets are connected the ends of the cross-bar. The cross-bar comprises two tubular sections 9 and 10, which are connected, respectively, to the brackets 7 and 8 and longitudinally through which is passed a bar 11.

This rod is secured to one tubular section by means of a transverse pin 12 passed through the rod and tubular section, there being a second transverse pin 14 passed through the rod and through the longitudinal slots 15 in the opposite tubular section. This connection permits of movement of the shaft sides relatively to each other, and this flexibility relieves the cross-bar of such strain as would break the usual cross-bar that is rigidly connected to the shaft sides.

It will be understood that in practice modifications of the specific construction shown may be made and any suitable materials and proportions may be used for the various parts without departing from the spirit of the invention.

What is claimed is—

1. A pair of shafts comprising side members and a cross-bar pivotally connected to the side members, said cross-bar comprising sections slidably connected for movement of the side members toward and away from each other.

2. A pair of shafts comprising side members and brackets attached to the side members and a cross-bar including sections pivotally connected respectively with the brackets, one of said sections being slidably engaged with the other section for movement of the said members toward and away from each other.

In testimony whereof I affix my signature in presence of two witnesses.

ABRAHAM BEVER.
